E. F. TUBACH,
MINE CAR DOOR.
FILED Dec. 30, 1921.

2 SHEETS-SHEET 2

UNITED STATES PATENT OFFICE.

EMIL F. TUBACH, OF DUSHORE, PENNSYLVANIA, ASSIGNOR OF ONE-HALF TO
ARTHUR L. TUBACH, OF DUSHORE, PENNSYLVANIA.

MINE-CAR DOOR.

Application filed December 30, 1921. Serial No. 525,962.

To all whom it may concern:

Be it known that I, EMIL F. TUBACH, a citizen of the United States, residing at Dushore, in the county of Sullivan and State of Pennsylvania, have invented certain new and useful Improvements in Mine-Car Doors; and I do declare the following to be a full, clear, and exact description of the invention, such as will enable others skilled in the art to which it appertains to make and use the same.

This invention relates to an improved mine car door and is an improvement over the construction shown in my prior Patent 1,221,112.

One object of the invention is to provide a car door of the type referred to wherein the door may be mounted in the rear end portion of the car by means of a rocker shaft for swinging movement into and out of a closed position and to so construct the rocker shaft that an extension thereof may be engaged by an improved type of latch to releasably hold the door against swinging movement to an open position.

Another object of the invention is to so construct the latch that it may of its own weight normally hang in an operative position with its bill portion extending over an arm extension of the rocker shaft.

Another object of the invention is to so construct and mount the latch that when moved to a releasing position, the arm extension of the rocker shaft may swing upwardly against the side of the bill portion of the latch and prevent the latch from moving to an operative or locking position until the door has returned to a closed position.

Another object of the invention is to so construct this latch that it may be operated by a person standing at one side of the coal car thus making it unnecessary for the operator to stand in front of the gate where he is liable to be injured by the gate swinging to an open position unexpectedly.

Another object of the invention is to provide an improved latch construction which may be very easily and quickly applied and which will be very strong and durable and easy to operate.

This invention is illustrated in the accompanying drawings, wherein:

Figure 1 is a view showing a mine car in end elevation with the improved end gate applied thereto.

Figure 2 is a view showing the rear end portion of the mine car in side elevation with portions thereof shown broken away.

Figure 3 is a view showing one side portion of the mine car in end elevation with the latch moved to a releasing position.

Figure 4 is a view similar to Fig. 2 showing the latch released and the door swung outwardly to its initial position after releasing of the latch.

Figure 5 is a view showing the car in a dumping position with the door swung open and material passing out of the car.

Figure 6 is a perspective view of the rocker shaft and latch.

The mine car which is indicated in general by the numeral 1 is provided with the usual wheels 2 so that the mine car may move along the rails 3 from the point of filling to the tipple where the car is to be emptied. The door is of a construction somewhat similar to that shown in the prior patent referred to and is provided with an upper section 4 and a lower section 5, the upper section and lower section being secured in spaced relation by inner and outer vertically disposed strips 6. The outer strips 6 extend beneath the lower edge of the door as shown in Figs. 2 and 4 so that the extended end portions of these outer strips may provide finger extensions 6' for engaging the abutment blocks 7 and cause the door or gate to move from the position shown in Fig. 2 to that shown in Fig. 4 when the latch is moved to a releasing position and the door receives its initial movement towards an open position. In order to mount the door for swinging movement into and out of a closed position, there has been provided a shaft 8 which extends longitudinally between the upper and lower sections of the door or gate and has its end portion bent to provide crank arms 9 which extend upwardly as shown and have their horizontally disposed end portions 10 journaled in bearing brackets 11 carried by the

car upon opposite sides of the open rear end. By having this gate mounted as shown, it will be permitted a swinging movement from the position shown in Fig. 5 to that shown in Fig. 4 when the latch is first released and will remain in the position shown in Fig. 4 until the car is tilted at the tipple as shown in Fig. 5. When the car is tilted as shown in Fig. 5, the gate will swing outwardly and the coal or other material passing out of the car will swing it to the position shown thus leaving the open rear end of the car clear so that coal may pass readily out of the car.

15 In order to releasably hold the end gate or door in a closed position, there has been provided a latch which is pivotally mounted by means of a pivot element 12 carried by a bracket 13 secured to the outer face of 20 the upper door section 4. This latch is provided with a bill portion 14 and a shank portion 15, the bill portion extending to one side of the shank portion and bent to extend outwardly from the door as clearly 25 shown in Figs. 2 and 4. The shank portion 15 extends downwardly and passes through an eye 16 carried by the lower door section 5 and is then bent to provide a handle extension 17 which extends through an eye 30 18 and terminates adjacent one side of the door. The bill portion 14 terminates adjacent the lower edge of the upper door section and when in the locking position extends above an arm 19 which extends outwardly from the shaft 8 in a substantially 35 horizontal plane. This arm extension 19 is formed by crimping the shaft intermediate its length. The adjacent portions of the door sections are cut away as shown at 40 so that the arm will be permitted a vertical swinging movement during movement of the gate to an open position. By having the latch pivotally mounted as shown and provided with the handle extension extending 45 towards the side of the gate, the latch will normally remain in the position shown in Fig. 1 with the bill portion extending above the arm 19 and therefore the latch will normally be in a position to prevent the 50 rocker shaft 8 from moving to permit movement of the gate to an open position. When however the latch is swung to the inoperative position shown in Figs. 3 and 4 and pressure of the coal against the gate swings 55 the gate outwardly to the position shown in Fig. 4, the arm will swing upwardly and by engaging one side of the bill portion of the latch, prevent the latch from returning to an operative position. The latch is to 60 be swung to the releasing position while the coal car is moving along the track and before it reaches the tipple. When the coal car reaches the tipple and moves to the dumping position shown in Fig. 5, the door 65 will be swung outwardly and upwardly to

the open position shown and will be held in this position by the coal which is passing out of the car. After the coal has passed out of the car and the door swings downwardly towards the closing position, the latch will again return to the operative position above the arm 19 and when the car has returned to the horizontal position on its way back to the place of filling, the door will swing inwardly and the lower end portions 75 6' of the outer strips 6 will drag over the abutments 7. The door will again be in the position shown in Figs. 1 and 2 and the car will be ready for filling. It should be noted that since the bill portion of the latch is 80 positioned above the arm 19, pressure of the coal against the door cannot cause a binding action between the bill and arm which would prevent the latch from being easily moved to a releasing position. It will also be noted that by having the latch constructed as shown, it can be formed from a single piece of metal and will be very strong and durable and of a simple construction.

While I have shown and described my invention as applied to a mine car, it will be understood that it may be used for other purposes such as the end gate of a truck or wagon.

I claim:

1. The combination with a door opening, of a door therein, a rocker shaft extending longitudinally of the door intermediate the height thereof and having its end portions in the form of cranks journaled in the sides 100 of the door opening, the shaft being provided with an arm extension intermediate its length extending outwardly of the door and having vertical swinging movement as the door and rocker shaft move, and latch means carried by the door for engaging the arm and releasably holding the door against movement towards an open position.

2. The combination with a door opening, of a door therein, a rocker shaft extending 110 longitudinally of the door intermediate the height thereof and having its end portions in the form of cranks journaled in the sides of the door opening, the shaft being provided with a horizontally disposed arm extension intermediate its length, and latch means movably carried by the door for extending above the arm extension to engage the same and hold the rocker shaft and door against outward swinging movement.

3. The combination with a door opening, of a door therein, a rocker shaft extending longitudinally of the door intermediate the height thereof and having its end portions in the form of cranks journaled in the sides 125 of the door opening, the shaft being provided with a horizontally disposed arm extension intermediate its length, and latch means pivotally mounted above the shaft for swinging movement into and out of 130

position above the arm, the latch when above the arm holding the arm against upward swinging movement and holding the door against outward movement to an open 5 position and the arm when moved upwardly engaging the latch to hold the latch in an inoperative position.

4. The combination with a door opening, of a door therein, a rocker shaft extending 10 longitudinally of the door intermediate the height thereof and having its end portions in the form of cranks journaled in the sides of the door opening, the shaft being pro- 15 vided with an arm extension intermediate its length, and a latch element carried by the door for swinging movement into and out of an operative position and having an operating element constituting a weight normally holding the latch in an operative po- 35 sition above the arm extension to engage the same and hold the door against outward movement.

5. The combination with a door opening, 10 of a door therein, a rocker shaft extending longitudinally of the door intermediate the height thereof and having its end portions in the form of cranks journaled in the sides of the door opening, the shaft being pro- 15 vided with an arm extension intermediate its length, and a latch element carried by the door for swinging movement into and out of an operative position, the latch when in an operative position engaging the arm extension to hold the door against outward 20 movement and the arm engaging the side of the latch when the door is moved to an open position to hold the latch in an inoperative position.

5. The combination with a door opening, 25 of a door therein, a rocker shaft extending longitudinally of the door intermediate the height thereof and having its end portions in the form of cranks journaled in the sides of the door opening, the shaft being pro-

vided with an arm extension intermediate its 30 length, and a latch element carried by the door for swinging movement into and out of an operative position and having an operating element constituting a weight normally holding the latch in an operative po- 35 sition above the arm extension to engage the same and hold the door against outward movement.

6. The combination with a door opening, 40 of a door therein, a rocker shaft extending longitudinally of the door intermediate the height thereof and having its end portions in the form of cranks journaled in the sides of the door opening, the shaft being pro- 45 vided with an arm extension intermediate its length, and a latch element carried by the door for swinging movement into and out of an operative position, the latch being pivotally mounted above the shaft and hav- 50 ing a depending arm-engaging bill portion and a depending shank portion extending downwardly to one side of the arm and provided with a handle portion extending longitudinally of the door.

In testimony whereof I have hereunto 55 set my hand.

EMIL F. TUBACH.
